UNITED STATES PATENT OFFICE.

WILLIAM ROEMER, OF NEWARK, NEW JERSEY.

TRAVELING-BAG CLIP.

SPECIFICATION forming part of Letters Patent No. 334,195, dated January 12, 1886.

Application filed June 15, 1885. Serial No. 168,665. (No model.)

To all whom it may concern.

Be it known that I, WILLIAM ROEMER, a citizen of the United States, residing at Newark, in the county of Essex and State of New Jersey, have invented certain new and useful Improvements in Handle-Fasteners for Traveling-Bags; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to gain increased strength in attaching the handle of a bag to the frame thereof, and to secure an attachment of increased utility.

The invention consists in the arrangements and combinations of parts, substantially as will be hereinafter set forth, and finally embodied in the clause of the claim.

Referring to the accompanying drawings, in which like letters indicate corresponding parts in each of the several figures, Figure 1 is a side elevation showing one end of the bag-handle and a portion of a bag-frame joined together by my improved connecting portions. Fig. 2 is a plan of a blank from which to form an end piece for the handle. Fig. 3 is a blank from which may be formed a loop, staple, ear, or connective for the frame of peculiar construction adapted to receive or provide bearings for the handle or the end piece thereof. Fig. 4 is a bottom plan showing the end piece after a certain tubular portion is formed, but before a bracing thereof is bent into proper shape. Fig. 7 is a side elevation of the completed end piece in detail. Fig. 5 is a side elevation, and Fig. 6 is an end elevation, of the completed loop or ear for the handle; and Fig. 8 is a side elevation, and Fig. 9 an end view, of a cap to cover extremity of the end piece and hold the latter to the said ear or loop.

In said drawings, *a* is the frame of the bag or satchel, and *b* is a handle attached thereto. *c* is the loop, clip, or ear; *d*, the end piece working therein, and *f* is the cap which covers the extremity of the said end piece and serves to hold said end piece in place.

The construction of the end piece and cap and their relation to the handle and to one another are very similar to those shown and

described in drawings and the specification 55 of another case filed at the United States Patent Office, together with this, Serial No. 168,666, dated June 15, 1885, and the claims relating especially to said parts are included in the other said case. This case, therefore, 60 relates more especially to the peculiar ear, loop, or connective and its relation to the other parts. Said loop is preferably formed from sheet metal, the blank being first struck out, as in Fig. 3, with a plurality of eyes *g g*, 65 which lie a little apart, the blank being narrowed, as at *h*, between them. At the opposite ends the blank is provided with perforated flanges *i i* at its narrowed part, forming vertical arms having eyes *g g*, which lie in or 70 approximately in line, as shown in Figs. 5 and 6, the narrowed part forming, when the several parts are together, a loop, to which a shoulder-strap may be secured. The eyes form double bearings for the cylindrical or 75 tubular portion of the end piece, giving increased firmness to the handle, the pivotal movement thereof being made more steady or positive. The lower ends or flanges of the portion *c* are outwardly bent, as shown, to be 80 firmly riveted. They may, however, be provided with simple lugs or rivets at the extremities.

The cylindrical portion of the end piece, *d*, is provided with an abutment, *m*, which limits its movement in one direction with respect to the portion *c*, while on the other side of the said portion the end or extremity is covered with the cap *f*, which prevents movement in the opposite direction, the cap being held upon 90 the end piece by a rivet, *n*.

Having thus described the invention, what I claim as new is—

The clip or ear *c*, having two vertical arms connected at the top by the narrower part *h*, 95 having the eyes *g g* in line with each other, and at its free ends means, substantially as described, by which said clip or ear is adapted to be secured to the satchel or bag frame, as set forth.

In testimony that I claim the foregoing I have hereunto set my hand this 28th day of May, 1885.

WILLIAM ROEMER.

Witnesses:

OLIVER DRAKE,
OSCAR A. MICHEL.
